DESIGN FOR A LEAF HOLDER

Richard Taylor, Chicago, Ill.

Application September 1, 1936, Serial No. 64,679

Term of patent 7 years

To all whom it may concern:

Be it known that I, Richard Taylor, a citizen of the United States, residing at Chicago, in the county of Cook and State of Illinois, have invented a new, original, and ornamental Design for a Leaf Holder, of which the following is a specification, reference being had to the accompanying drawing, forming part thereof.

I claim:

The ornamental design for a leaf holder, as shown.

RICHARD TAYLOR.
